CLAIM

The ornamental design for a bag, as shown.

DESCRIPTION

FIG. 1 is a top plan view of the bag showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof, with the strap of the bag removed for convenience of illustration;

FIG. 7 is a front perspective view thereof;

FIG. 8 is a front perspective view thereof showing the lid in an alternative position and the bag open; and,

FIG. 9 is a front perspective view thereof showing an additional alternative top lid part.

The broken line showing of environment is for illustrative purposes only and forms no part of the claimed design.
